(57) **CLAIM**

The ornamental design for a mounting clip, as shown and described.

DESCRIPTION

FIG. 1 is a front perspective view of a mounting clip showing my new design;

FIG. 2 is a side elevational view of one side thereof;

FIG. 3 is a side elevational view of the other side thereof;

FIG. 4 is a top plan view thereof;

FIG. 5 is a bottom plan view thereof;

FIG. 6 is a front elevational view thereof; and,

FIG. 7 is a rear elevational view thereof.

The broken line showing in FIGS. 2 & 3 of triangular indentations near the top portion of the clip and the broken line showing in FIGS. 4 & 5 of a mounting hole are for illustrative purposes only and form no part of the claimed design.
